UNITED STATES PATENT OFFICE.

CHARLES ANDERSON, OF CHICAGO, ILLINOIS.

WHEELWRIGHT-MACHINE.

SPECIFICATION forming part of Letters Patent No. 244,365, dated July 19, 1881.

Application filed March 8, 1881. (Model.)

To all whom it may concern:

Be it known that I, CHARLES ANDERSON, of Chicago, county of Cook, and State of Illinois, have invented a new and useful Machine 5 for Inserting and Spacing the Spokes in the Fellies of Wheels; and I do hereby declare that the following is a full, clear, and exact description and specification of the same, reference being had to the accompanying drawings, making part thereof.

My invention relates to the manufacture of boys'-wagon wheels and toy-cart wheels composed of a hub, spokes, and felly.

Before my invention the spokes, after being 15 secured in the hub, were entered within the smooth inner circle of the felly one at a time, and spaced by hand.

My invention consists in a machine having 20 certain combinations of parts, specifically set forth in the claims at the end of this schedule, by which all the spokes are entered, spaced equally, and secured in their appropriate places in the felly at the same time, thereby saving time and obtaining greater uniformity.

25 In order that persons skilled in the art may understand, make, and use my invention, I will proceed to describe it, referring to the drawings, in which—

Figure 1 is a plan view of my machine, with 30 portions broken away to show the parts beneath. Fig. 2 is a side elevation of the same, the frame I and the parts connected thereto being removed. Fig. 3 is a side elevation of the frame I and the parts connected to it removed from the table E.

Table E, supported by the legs Z, is the bed-plate of the machine. It is provided with radial slots D, in which are fastened the slides C by means of screws y y, which screw into 40 the bottoms of the slides from the under side of the table E through the slots D. The slides C C can be adjusted radially from the center post, H, and fastened by these screws, to adapt the machine to operate upon different sizes of 45 wheels. The center post, H, projects above the table E, and at its bottom rests upon the cross-brace L. It is shouldered down at N to provide a rest for the hub of the wheel, which is held centrally by spindle M while the spokes 50 and felly are being operated upon. The ra-

dial slides C are slotted and provided with pivots W W, on which the forked levers B B vibrate. The upper ends of the latter are V-shaped to hold the spokes, and provided with shoulders i i to support the felly of a wheel 55 while being operated upon. The levers pass through slots D D, and are jointed beneath the table to the outer ends of connecting-rods F F. The other ends are held by a wire, Q, in the grooved circumference of plate G, so 60 that they move with it up and down. The plate G on the center post, H, rests upon a coil-spring, O, which rests upon the collar S, fixed by a set-screw to the post H. It and its connecting parts are drawn down by means of 65 the foot-lever T, which is attached to it by suspension-rods V V, hooking into eyes R R in the plate G and into holes in the lever T, pivoted at one end to an ear, v, under the cross-brace L. When plate G is drawn down it 70 compresses the spring O upon the collar S. At the same time the lower ends of the levers B B are drawn inward and their upper ends are thrown outward, so that the felly of the wheel resting upon the shoulders i i is expanded. 75 When the operator wishes to restore the parts to their former position, as shown in the drawings, he removes his foot from the lever T, and the spring O forces up plate G, which draws the upper ends of levers B B in, so that he 80 may remove the wheel just operated upon and place another one in position. Cross-brace L is fastened to side connections, which join together and brace the legs of the machine near their lower ends.

Above the table E is a cross-bar, I, supported on upright posts K K. This cross-bar supports the mechanism which raises, lowers, supports, and sets free the drop-plate A. A pulley, f, secured to shaft d, which is held in bearings e e' on brackets c c', has attached to it one end of a wire rope, g, while the other end is fastened to about the center of drop-plate A, so that when the pulley f is turned the plate A will be raised or lowered.

On the outer end of shaft d is fixed a crank-disk plate, h, provided with a notch in its circumference, into which a pawl, m, secured to bracket c', catches to hold the plate A in its highest position. When the pawl m is thrown 95 100

out of the notch in crank-disk *h* the plate *A* will drop upon the spokes and hub of a wheel placed in position.

On the circumference of the plate *A* notches *b b* are made, leaving between them tongues *a a*, which strike upon the ends of the spokes of the wheel placed in position over the **V** in the ends of the levers *B B*, and when the plate *A* drops, should the spokes not be correctly spaced, they will be guided by the sides of the **V** and the tongues *a* of the drop-plate into correct positions for fastening to the felly.

The operation of my machine is as follows: The plate *A* being at its highest position and held by the pawl *m*, the felly of a wheel, with a smooth inner surface, is placed upon the shoulders *i* of the expanding-levers *B B*. The hub, provided with spokes without tenons on their ends, is then placed on the center spindle, *M*, resting on the shoulder *N*, so that the spokes lie within the **V**-jaws of the expanding-levers *B B* and project over and beyond the smooth inner circle of the felly. The parts of the machine being in the positions indicated in the drawings, the operator forces down the lever *T* with his foot, which causes the upper ends of the levers *B B* to expand the felly placed on them outward. The operator then releases the pawl *m* and the plate *A* drops upon the ends of the spokes, which forces them into the inclosure of the felly in their proper places. The felly is then pinned to the ends of the spokes, which completes the operation. The **V**-shaped jaws of the levers *B B* direct and space the spokes to their correct positions in the felly when the plate *A* descends upon them.

The slides *C C* may be moved nearer the center spindle, *M*, for toy-cart wheels or farther away for boys'-wagon wheels. One position 40 for wheels like those for baby toy carriages is indicated at *B' B'*, the plate *A* being provided with holes to receive the ends of the levers.

Having now fully described my invention and the manner in which I have embodied it, 45 what I claim as my invention, and desire to secure by Letters Patent, is—

1. The combination, substantially as herein-before set forth, of the table, with the shoulered and forked holding-guides, pivoted and 50 connected to expand and to hold the felly, and to hold, guide, and space the spokes of a wheel, all constructed and operating substantially in the manner and for the purposes specified.

2. The combination, substantially as herein-before set forth, of the table, the felly-expanding and spoke-spacing levers, and the levers under the table, with the treadle for actuating the same, all constructed and operating substantially in the manner and for the purposes 55 specified.

3. The combination, substantially as herein-before set forth, of the table, the felly-expanding levers, the levers under the table, with the treadle for actuating the same, and the drop-plate for forcing the spokes of a wheel into their places in the felly, all constructed and operating substantially in the manner and for the purposes 60 specified.

CHARLES ANDERSON.
